UNITED STATES PATENT OFFICE.

LEVI N. BACHAND, OF CHICAGO, ILLINOIS, ASSIGNOR OF ONE-HALF TO
WILLIAM J. GARVY, OF SAME PLACE.

FOLDING BED.

SPECIFICATION forming part of Letters Patent No. 653,409, dated July 10, 1900.

Application filed December 22, 1896. Renewed February 23, 1900. Serial No. 6,297. (No model.)

To all whom it may concern:

Be it known that I, LEVI N. BACHAND, a citizen of the United States, residing at Chicago, in the county of Cook and State of Illinois, have invented a certain new and useful Improvement in Folding Beds, (Case No. 2,) of which the following is a full, clear, concise, and exact description, reference being had to the accompanying drawings, forming a part 10 of this specification.

My invention relates to beds of that class commonly known as "folding" beds, which are formed of sections which in a closed position impart to the bed the appearance of a 15 small article of furniture, as a chiffonnier or bookcase, and in an open position put the bed in condition for use as such.

My invention comprises improvements in this class of beds, which will be explained in 20 connection with the accompanying drawings, in which—

Figure 1 is a front elevation of my improved folding bed open in condition for use, the bedding being shown in dotted lines to reveal 25 parts hidden thereby. Fig. 2 is a front elevation of a portion thereof, showing the end sections of the bed-body folded at right angles to the intervening middle section, in which condition the bed-body is swung into 30 a vertical position of disuse. Fig. 3 is a detail of the mechanism. Fig. 4 is a side elevation of the bed, the bed-body being shown in full lines as being slightly tilted, its horizontal and vertical positions being shown by 35 dotted lines. Fig. 5 is a front elevation of the bed after being folded up. Figs. 6 and 7 are detail views of a portion of the mechanism.

Like letters indicate like parts throughout the different figures.

40 The framework of the bed is preferably of angle-steel, as shown in Figs. 1 and 6, for the sake of lightness and strength.

The bed-body is preferably composed of three sections a b c , hinged or pivoted together in a manner to permit the end sections a and c to be folded at right angles to the central section b , the frame-pieces a' c' of the sections a c being hinged to the frame-pieces b' b' of section b . Rotation of the sections a c toward 45 each other beyond this right-angled position is prevented by extensions a^2 c^2 , which engage

55 with the frame-pieces b' b' , as shown in Fig. 2 and more clearly in Fig. 6. The end sections of the bed-body are maintained at right angles to section b by a strap d , which is secured at one end to the foot-rail c^3 of section c and at the other end is provided with a hook adapted to be inserted within an eye d' , secured to the head-rail a^3 of section a .

60 The head and foot pieces e f are pivotally secured to side pieces e f in a manner to permit the rotation thereof to engage the bedding and secure the same in a position conforming to the folded bed-body, as clearly shown in Fig. 2. By this construction the 65 folds of the bedding are prevented from lying close together, whereby thorough ventilation is afforded to the bedding after the bed has been folded and disarrangement of the bedding is prevented.

70 The bedding is supported upon a woven-wire mattress g , secured to the end rails of the bed-body, said mattress lying in a plane below the joints between the frame-pieces a' b' and b' c' when the bed is open, whereby 75 any weight superimposed thereon tends to lower the sections a c , the possibility of the bed folding upon the occupant being thus prevented. To afford additional support, I provide a supplemental mattress g' , composed 80 of vertically-disposed coiled springs placed between the middle portion of the mattress g and the section b .

85 The bed-body as a whole is preferably supported upon a base-frame i , the supports consisting of links k , rotatably secured at their ends to the transverse ribs b^2 of the section b , as shown in Fig. 4. The bed-body is adapted to be swung upon the links k in a manner to be hereinafter described, the bed-body being 90 provided with legs l l , adapted to coact with the links k in supporting the bed-body in a horizontal position. In order that manual adjustment of the legs may be obviated, I provide link connections m between the legs 95 l l and the links k , these links m serving to throw the legs l to a position perpendicular to the floor when the bed is lowered and to cause said legs to lie parallel with the bottom of the bed-body when it is folded and raised 100 to a vertical position. A brace-piece n is preferably rigidly secured to the middle section

b of the bed-body, to which in turn are preferably rigidly secured the arms *o o*, which are provided with extensions at right angles thereto, which are adapted to travel within 5 vertical guides, guideways, or grooves *p'*, (shown most clearly in Fig. 3,) provided in the vertical frame *p*, as the bed-frame is raised and lowered, whereby the bed is guided as it is being swung. Within these grooves are also 10 disposed the extension rods or portions *q' q'* of the canopy *q*, which are capable of vertical excursion therein. The canopy is elevated and lowered as the bed is lowered and raised, the extension-rods *q' q'* and the arms *o o*, engaging the same, being provided for this purpose. I thus form a folding bed with a vertically-moving shelf or canopy which is lowered to a convenient height when the bed is folded, so that decorative or other articles may 15 readily be placed on and removed therefrom, while when the bed is unfolded for use the shelf is raised a sufficient distance to give freedom to the occupant. The canopy may be of a fanciful design in itself, however, in 20 which case it may not serve to support articles. By lowering and raising the canopy when the bed is folded and opened I give to the bed when folded or opened artistic proportions. I preferably construct a canopy of 25 such a size that when the curtains are suspended at the edges thereof they will hang straight down over the sides of the bed when folded. The canopy I have shown is solid; but it is obvious that canopies of other construction projecting from the extension-rods 30 *q' q'* may be employed.

It will be observed that the vertical frame is disposed between the two end sections of the bed. The middle section of the bed 40 practically corresponds in length to the width of the vertical frame. By this construction either end of the bed may be used as the head.

It being desired to close the bed from the open position, (shown in Fig. 1,) the sections 45 *a* and *c* are turned at right angles to the section *b*. The head and foot pieces *e f* are then rotated to engage the bedding to secure the same in position conforming to the folded bed-body, and the sections *a b c* secured in their 50 adjusted positions by the strap *d*, as shown most clearly in Fig. 2. The handle *r* is then grasped and the bed-body swung as a whole upon the links *k* to a vertical position. The canopy *q*, which had been previously elevated 55 by the arms *o o* when the bed was lowered, now becomes lowered as the bed is raised. It will thus be seen that I provide a mounting for the bed which permits the same to swing in a vertical plane perpendicular to the 60 head or vertical frame of the bed. As the bed is being folded into position the canopy is preferably limited in its downward movement by the molding *q²* engaging the top portion of the frame *p*, as the high point of the body of 65 the bed in swinging reaches the canopy, since a further downward movement of the canopy will prevent the bed from being completely

folded. The point at which the molding engages the frame *p* is determined by the length of the extension rods or portions *q² q²*. The 70 downward motion of the canopy may be otherwise limited.

Behind the movable canopy I provide a mirror *s*, which may at all times be apparent. A board or portion *s'*, which preferably partakes 75 of the character of the mirror-frame and which fits between the inner vertical borders thereof, is carried by the canopy and fits at the top thereof when the bed is lowered, as shown in Fig. 1 and in dotted lines in Fig. 5, the mirror beneath the same being revealed. When the bed is raised, the board *s'* is lowered with the canopy, as shown in full lines in Fig. 5, the portion of the mirror above the same being 80 revealed.

To conceal the character of the bed when folded, I prefer to employ curtains *t t'*, which may be draped from the canopy, as shown.

To remove the bearing strain from the pivots uniting the links *k* to the bed-body, a portion 90 of each of said links, which are constructed of angle-iron, is cut away to form shoulders *u*, as shown most clearly in Fig. 7, upon which the bed-body is adapted to rest when the bed is unfolded.

While I have thus particularly described the precise forms of the features of my invention, I do not desire to be limited to the precise construction shown, as modifications 95 may readily be made without departing from the spirit of my invention; but,

Having thus described my invention, what I claim as new, and desire to secure by Letters Patent, is—

1. In a folding bed, the combination of a 105 rotatably-mounted bed-body formed in three sections, the end sections being adapted to be folded substantially at right angles to the middle section, with means for securing said sections in this angular adjustment, and rotatably-supported head and foot pieces *e f* 110 adapted to secure the bedding in position conforming to the position of the folded sections, substantially as and for the purpose described.

2. In a folding bed, the combination of a 115 bed-body formed in three sections adapted to be folded substantially at right angles to each other, means for securing said sections in this angular adjustment, and a base-frame 120 with supporting-links *k* rotatably secured to said base-frame and bed-body, arms *o o* secured to said bed-body, a vertical frame provided with guideways, a canopy provided with extension-rods which are adapted to be 125 engaged by said arms *o o* and to travel within said guideways, substantially as and for the purpose described.

3. In a folding bed, the combination with 130 vertical guides, of vertically-movable extension rods or portions *q' q'* adapted to be guided in their travel by said guides, a canopy rigidly secured to said extension-rods, a bed, a mounting therefor adapted to permit the bed to swing in a vertical plane, the frame of the

bed having engagement with the extension-
rods $q' q'$ whereby as the bed is raised and
lowered the canopy is lowered and raised, sub-
stantially as described.

5 4. In a folding bed, the combination with
vertically - movable extension - rods $q' q'$, a
canopy rigidly secured thereto, vertical guides
adapted to guide the extension-rods in their
travel, a bed having a mounting which per-
mits the bed to swing in a vertical plane,
arms $o o$ rigidly secured to the bed and en-
gaging the extension-rods $q' q'$ whereby as the
bed is raised and lowered the canopy is low-
ered and raised, substantially as described.

15 5. In a folding bed, the combination with
vertically - movable extension - rods $q' q'$, a
canopy supported thereby, vertical guides
adapted to direct the extension-rods in their
travel, a bed, a mounting therefor permitting
20 the bed to swing in a vertical plane, arms $o o$
rigidly secured to the bed having separable
engagement with the extension-rods and also
being engaged and directed in their move-
ment by said guides, and means for limiting
25 the canopy in its downward travel as the bed
is being swung into its folded position, the
arms $o o$ thereupon being disengaged from
the extension-rods during the rest of the move-
ment of the bed, substantially as described.

30 6. In a folding bed, the combination with
a bed-body formed in a middle and two end
sections, the end sections being adapted to be
folded substantially at right angles to the
middle section, of means for securing said
35 sections in this angular adjustment, and
swinging head and foot pieces adapted to se-
cure the bedding in a position conforming to
the position of the folded sections, substan-
tially as and for the purpose specified.

40 7. In a folding bed, the combination with
a bed-body divided in its length into three
sections, the end sections being adapted to be
folded substantially at right angles to the
middle section, means for securing the sec-
45 tions in this angular adjustment, a vertical
frame between the end sections and contigu-
ous to the middle section, the bed having a
mounting at its central portion which permits
it to be swung in a vertical plane to a posi-
50 tion in front of the vertical frame, either end
of the bed being thus adapted to be used as
the head when unfolded, substantially as de-
scribed.

8. In a folding bed, the combination with
55 a bed-body, of supports k and l , the supports
 k being linked at their upper ends to the
frame of the bed and pivotally mounted at
their lower ends, while the supports l are

linked at their upper ends to the bed-frame,
links m uniting supports l with supports k , 60
and a vertical frame p against which the bed-
body is adapted to rest when the bed is un-
folded, the supports k inclining toward the
vertical frame when the bed is unfolded, the
latter supports in their movement being 65
adapted to thrust the supports l outwardly
through the medium of the links m when the
bed is lowered and to draw said supports l
close to the bed when it is elevated, substan-
tially as described. 70

9. In a folding bed, the combination with
a bed-body, of supports k and l , the supports
 k being linked at their upper ends to the
frame of the bed and pivotally mounted at
their lower ends, while the supports l are 75
linked at their upper ends to the bed-frame,
links m uniting supports l with supports k , a
vertical frame p against which the bed-body
is adapted to rest when the bed is unfolded,
the supports k inclining toward the vertical 80
frame when the bed is unfolded, the latter
supports in their movement being adapted to
thrust the supports l outwardly through the
medium of the links m when the bed is low-
ered and to draw said supports l close to the 85
bed when it is elevated, and an attachment
to the bed having sliding engagement with
the vertical frame, substantially as described.

10. In a folding bed, the combination with
a rotatably-mounted bed-body, of a vertically- 90
movable canopy, guiding means for directing
the travel of said canopy in a vertical direc-
tion, said bed having separable engagement
with said canopy, and means for effecting the
separation of the bed-body and canopy for 95
limiting the canopy in its downward move-
ment as the bed is being swung to a folded
position, substantially as described.

11. In a folding bed, the combination with
vertical guides, of vertically-movable exten- 100
sion rods or portions adapted to be guided in
their travel by said guides, a dresser top or
canopy secured to said extension-rods, a bed,
a mounting therefor adapted to permit the
bed to swing in a vertical plane, the frame of 105
the bed having engagement with the exten-
sion-rods, whereby as the bed is raised and
lowered, the dresser top or canopy is lowered
and raised, substantially as described.

In witness whereof I hereunto subscribe my 110
name this 11th day of July, A. D. 1896.

LEVI N. BACHAND.
